UNITED STATES PATENT OFFICE.

SHELBY E. SIMMONS, OF RUSSELLVILLE, KENTUCKY.

MOVABLE HEADLIGHT FOR LOCOMOTIVES.

1,081,992.

Specification of Letters Patent. Patented Dec. 23, 1913.

Application filed July 9, 1913. Serial No. 778,136.

To all whom it may concern:

Be it known that I, SHELBY E. SIMMONS, a citizen of the United States, residing at Russellville, in the county of Logan and State of Kentucky, have invented a new and useful 5 Movable Headlight for Locomotives, of which the following is a specification.

This invention relates to improvements in movable headlights for locomotives and 10 more particularly to an apparatus in which the locomotive headlight is automatically turned as the locomotive encounters a curve.

An object of the present invention is to provide a locomotive headlight which is 15 turned by and proportional to the inclination of the locomotive for the continual illumination of the track.

A further object is to provide oppositely disposed communicating cylinders with 20 floats arranged therein and secured to the headlight so that changes in the corresponding levels of the liquid contained within the said cylinders will produce corresponding changes in the line of propagation of the 25 light.

A further object is to provide a headlight turning apparatus wherein the time element may be varied.

With the foregoing and other objects in 30 view which will appear as the description proceeds, the invention resides in the combination and arrangement of parts and in the details of construction hereinafter described and claimed, it being understood that 35 changes in the precise embodiment of the invention herein disclosed, can be made within the scope of what is claimed, without departing from the spirit of the invention.

40 In the drawings accompanying this specification and forming a part thereof, the preferable form of my invention is illustrated, in which:—

Figure 1 is a view of my device with portions thereof removed and illustrating the 45 outline of the boiler of a locomotive to illustrate the respective relations of the various parts. Fig. 2 is a top plan view of the foregoing.

50 Referring to the drawings in which similar reference numerals designate corresponding parts throughout the several views, 3 is the locomotive boiler around which the liquid containing portion of my apparatus fits so that the heat derived therefrom will be sufficient to prevent the freezing of the

liquid within the liquid containing portion of the apparatus despite climatic conditions.

Rigidly secured and upon opposite sides of the boiler 3 are the open-ended cylindrical tanks 4 which are provided with the gage glasses 5 for obvious reasons. Extending between the lower portions of the cylindrical tanks 4 and bringing the same into communication is the conduit or pipe 6, the same being provided with a suitable valve 7 therein and which is adapted to control the time element, by which is meant the time required for a change in the level of the track to produce a corresponding or functional change 70 in the line of light propagation of the headlight. The members 4 and 6 constitute a U-tube with the upstanding legs 4 thereof disposed upon opposite sides of the locomotive boiler. A suitable pet-cock 8 is secured to 75 the pipe 6 and provides a suitable drain therefor. As illustrated in Fig. 1 of the drawings there are three retaining flanges 9 secured to the U-tube and to the sides of the locomotive boiler. However, the exact 80 means of attachment constitutes no part of the present invention, it only being necessary that the said tube be rigidly held to the boiler and prevented from any relative movement with respect thereto.

Extending upwardly from the top extremities of the cylindrical tanks 4 is the circular strip 10 conforming to the outline of the boiler and supporting a stationary 90 headlight carrying carriage thereabove.

Pivotaly secured to the carriage or frame 11 is the headlight 12 of conventional type, there being suitable trunnions 13 extending therefrom so as to pivotally secure the said headlight to the frame and capable of rotating about a vertical axis so that the line of light propagation may be shifted in a horizontal plane. Secured to and extending rearwardly from the headlight is the lever 14 to which are adjustably secured the diverging flexible elements 15.

Mounted within the cylindrical tank 4 and slidably disposed with relation thereto are the open-ended floats 16, each of which is provided with a suitable air valve 17. It is 105 possible to vary the weights of the floats to cause corresponding changes in the inertia thereof.

The flexible elements 15 are passed through suitable guides 18 which are positioned centrally above the open ends of the cylindrical tanks and after which the said

flexible elements pass downwardly into the cylindrical tanks and are permanently secured to the floats.

It is to be noted that there is a suitable cap 4' removably secured to the open ends of the cylinders 4 whereby the accumulation of foreign material within the cylinders will be prevented.

The operation of my device is substantially as follows:—A suitable liquid is introduced within the U-tube and by means of the pet-cock 8 and the gage glasses 5 the normal level thereof is suitably adjusted. As the locomotive encounters a curve, the banking thereof causes an inclination of the locomotive and which inclination will vary the respective levels of the liquid or mobile element within the cylindrical tanks 4 taken with respect to some reference line upon the tanks themselves. Thus a corresponding movement of the floats will take place with the result that the headlight will be rotated about a vertical axis due to the connection with the floats by reason of the flexible elements 15. Although centrifugal force will tend to neutralize the movements of the liquid caused by the inclining of the locomotive, it has been found that with the locomotive traveling at a normal rate of speed, the centrifugal force does not entirely neutralize the effect due to the banking of the track, taken with respect to the liquid or mobile element. It has been found in practice that in order for the various parts to properly respond, some means must be provided for controlling the flow of liquid between the two cylindrical tanks as the respective levels thereof are varied. This may take the form of reducing the pipe 6 as illustrated or by introducing the valve 7 whereby a quick and ready adjustment can be obtained. Also the density of the liquid can be varied and which will cause a variation of the time element as it is thought will be clearly apparent. Mention is also made of the fact that the weights of the floats can be easily adjusted to vary the inertia thereof.

The device herein disclosed can be used upon other moving vehicles traveling upon rails besides locomotives, without varying from the spirit of the invention.

What is claimed is:—

1. In an apparatus of the class described, the combination of spaced communicating liquid containing tanks, a movable light, floats disposed within the said tanks and connected to the said light to control the movements thereof, and means for varying the time lapsing between a change in the levels of the tanks and the corresponding movement of the light.

2. In an apparatus of the class described, the combination of upstanding open spaced liquid receiving communicating tanks, floats disposed therein and means for varying the weights thereof, a headlight mounted for rotation about a vertical axis, flexible elements connected to the floats and to the said headlight, means for varying the weights of the said floats to cause corresponding variations in the inertia thereof, and means for varying the time lapsing between a change of levels of the communicating tanks and the corresponding movement of the headlight. 75

3. In an apparatus of the class described, the combination with a locomotive boiler, of a U-tube positioned around and adjacent the lower portion of said boiler and adapted to be heated thereby, said tube adapted to contain a mobile element therein, floats disposed within the legs of said U-tube, means for regulating the flow of liquid between said legs, a movable light propagating source, and means extending between the said floats 85 and the said light propagating source adapted to control the movements of the latter.

4. In an apparatus of the class described, the combination of communicating liquid containing tanks, floats slidably disposed therein, a valve controlling the flow of liquid between the said liquid containing communicating tanks to thereby control the time lapsing between a change in the levels of the liquid in the tanks and the corresponding movement of a rotating element, and an element mounted for limited rotation, and means extending between said element and said floats for controlling the movements of 95 the former by and with the latter. 100

5. In an apparatus of the class described, the combination of spaced liquid containing tanks, a tube extending therebetween and communicating therewith, inverted cup-shaped floats slidably disposed within said tank, means for regulating the volume of air within the upper portion of said inverted cup-shaped floats, to thereby regulate the buoyancy of said floats, a movable light 110 propagating source, and means extending between said floats and said light propagating source adapted to control the movements of the latter with and by the former. 105

In testimony that I claim the foregoing 115 as my own, I have hereto affixed my signature in the presence of two witnesses.

SHELBY E. SIMMONS.
